UNITED STATES PATENT OFFICE.

SYLVANUS B. ROY, OF WORCESTER, MASSACHUSETTS.

GEARING FOR SPINNING OR TWISTING MACHINES.

1,081,334.

Specification of Letters Patent. Patented Dec. 16, 1913.

Application filed December 17, 1907. Serial No. 406,859.

To all whom it may concern:

Be it known that I, SYLVANUS B. Roy, a citizen of the United States, residing at Worcester, in the county of Worcester and 5 State of Massachusetts, have invented a new and useful Gearing for Spinning or Twisting Machines, of which the following is a specification.

The object of this invention is to provide 10 a new and improved gearing for spinning machines so that the same may be arranged to spin and draw yarn to have slubs or flakes formed therein, which slubs or flakes are formed by lightly drawn or undrawn 15 sections.

To this end, the invention consists in combining with the gearing for giving the feeding rolls their usual rotation, improved and simplified means for giving the same an 20 additional quick forwarding rotation so that the yarn intermittently will have a quick advance between the feeding and drawing rolls which will cause the yarn to have sections along its length which are slightly 25 drawn or undrawn.

The preferred mechanism for imparting this peculiar movement comprises gearing for giving the feeding rolls their usual rotation, which gearing may include a ratchet- 30 wheel and pawl, the driving of the feeding rolls being done through the pawl acting on the ratchet-wheel, and mechanism, preferably a mutilated gear and pinion, for giving the ratchet-wheel a quick advancing 35 motion beyond the motion imparted by the pawl. In some cases, a system of mutilated gearing may be used in place of the ratchet and pawl mechanism.

The invention is shown in the accompanying 40 two sheets of drawings which illustrate enough of an ordinary form of spinning and drawing frame to show how my improvement may be applied thereto.

Referring to the drawings and in detail, 45 Figure 1 is a side elevation of the frame. Fig. 2 is a sectional plan view through the rolls taken along the plane of the yarn. Fig. 3 is a view showing the yarn with slubs or flakes therein. Fig. 4 is a side elevation of a modified form of gearing which 50 may be employed to obtain the same result. Fig. 5 is a side elevation, and Fig. 6 is a front elevation of another modified form of gearing.

55 Referring to the drawings in detail, the preferred form of the mechanism illustrated

in the first sheet of drawings will first be described. In detail, A designates the frame, B one of the spools which carry the roving, and C one of the spindles which rotates the 60 usual bobbin which receives and spins the yarn.

In the drawings, the invention is shown as applied to a cap spinning frame in which E designates the cap surrounding the bobbin, although it is to be understood that my invention can be applied to any form of spinning machine. The roving is pulled from the spool B by feeding rolls 10-10; is passed forward through three sets of unweighted 70 intermediate rolls 11-11, 11-11, 11-11 and is drawn or pulled out by the drawing rolls 12-12, the drawing rolls 12 having a faster peripheral speed than the feeding rolls 10-10 to draw out the roving in the usual 75 way. The roving passes from the drawing rolls 12-12 through any of the usual thread-guides T to the bobbin D. These parts may be arranged in the usual ways and further description of their operation is not necessary.

The unweighted intermediate rolls are arranged to have a slight drawing action upon the roving, but their chief function is to retain the twist in the roving as it approaches the drawing rolls. If the intermediate rolls are omitted, the long stretch of roving between the rolls 10 and the rolls 12 has a tendency to untwist and break between the rolls, and it is found unpracticable 90 to operate the machine without the intermediate rolls being in position.

The gear for driving the feeding rolls and as many as desired of the intermediate rolls in the manner previously referred to is arranged as follows: 13 designates a driving or power shaft which is rotated from any of the usual mechanism of the machine or which may form an extension of one of the shafts of the drawing rolls 12-12. The 100 shaft 13 has a pinion 14 mounted thereon which engages and drives a gear 15 loosely running on a stud 16. Connected to turn with, or formed as an integral part of the gear 15, is a mutilated gear 17 which has a 105 small section of teeth 170 and also formed or secured to the gears 15 and 17 is a gear 18, the gears 15, 17 and 18 turning as one piece and the mutilated gear 17 being larger than the gear 18. The shaft of the lower feeding 110 roll 10 is extended out as at 19 and secured thereon is a pinion 20 which is set in po-

sition to be engaged by the teeth of the mutilated gear 17. Loosely mounted on the shaft 19 is a gear 21 which is in constant mesh with the gear 18. This loose gear 5 carries on its side a pawl 22 which is pressed by a spring 23 to engage a ratchet-wheel 24 secured or fixed on the shaft 19. As many of the intermediate rolls may be geared to receive the peculiar motion imparted to the feeding rolls as desired.

In the device illustrated in the drawings, the lowermost intermediate roll is turned continuously by any of the usual forms of gearing not necessary to describe, but the 15 other two intermediate rolls 11-11 are geared to have the peculiar motion given to the feeding rolls 10-10. This may be continuously done by placing a pinion 25 on the shaft 19, which pinion engages an intermediate 26 loosely mounted on a stud 27, which intermediate engages a pinion 28 secured on the central lower intermediate roll 11. The rear-most lower intermediate roll 11 may be driven by a pinion 29 secured on 25 the lower feeding roll 10, which pinion engages an idle or intermediate gear 30 mounted on a stand 301 secured to the frame of the machine. The idle gear 30 engages and drives a pinion 302 secured on the rear, 30 lower intermediate roll 11, said roll accordingly partaking of the intermittent motion of the shaft 10. The lower of the drawing rolls 12 is formed on the driving or power shaft 13. The stud 16 on which the three 35 gears 15, 17 and 18 revolve may be secured in a bracket 31 which is held to the frame by a bolt 32, and the stud 27 on which the intermediate 26 revolves may be mounted in a bracket 33 which is secured to the frame 40 of the machine.

In operation, the feeding rolls 10-10 are driven continuously at an even speed through the pinion 14, gear 15, gear 18, loose gear 21, pawl 22, and ratchet-wheel 24. 45 If this relation is not disturbed, the feeding rolls will turn at an even and continuous speed, but when the small section of teeth 170 of the mutilated gearing 17 engages the fixed pinion 20, the shaft 19 will be turned 50 forward much more rapidly, the ratchet-wheel 24 during this operation moving forward under the pawl, the pawl allowing this forward movement of the ratchet-wheel as the ratchet-wheel teeth are made saw-like 55 in shape for this purpose. This will cause a much quicker turning action of the feeding rolls 10-10 while the gear teeth 170 are in operation and hence will cause a quick intermittent movement or forward jump of 60 the yarn beyond the feeding rolls 10-10. This will form a slub or flake in the yarn as this quickly advanced section will be lightly drawn by the action of the drawing rolls 12-12 or not drawn at all. By properly 65 proportioning this gearing, the flakes can

be made as long or as short as desired and can be made to come at any desired points length-wise of the yarn. By putting a plurality of sections of teeth 170 around the gear 17, the number of slubs in the length 70 of yarn also can be varied in a convenient way.

When it is desired to use the spinning machine in an ordinary way, all that is necessary is to put the mutilated gearing out 75 of operation. This can be done by sliding the pinion 20 back on the shaft 19, by taking the mutilated gear 17 off of the stud 16, or by disconnecting this gearing in any other way. In practice, the small section of teeth 80 170 of the mutilated gear 17 is made as a separate part and another way this gearing can be disconnected is to take out this short section of teeth.

In Fig. 4 a device is provided whereby 85 the ratchet-wheel and pawl are not used. In this construction, a gear 180 is used corresponding to the gear 18 of the previous device but this gear 180 is only provided with teeth part way on its circumference and the gear 210 on the shaft 19 with which the gear 180 meshes is fast on the shaft 19. The space in the teeth on the gear 180 is set 90 to correspond with the teeth 170 of the mutilated gear 17 whereby when the teeth 170 95 take into the fixed pinion 20 to turn the shaft at its accelerated speed, the gears 180 and 210 will be out of mesh so that this action can take place. During the rest of the 100 operation, the shaft 19 will be driven at a continuous speed by the teeth of the gear 180 meshing with the teeth of the gear 210.

In the modification shown in Figs. 5 and 6, the gear 18 meshes with a gear 35 which is loosely mounted on the end of the shaft 19, which gear 35 carries a spring-pressed pawl 36 which engages a ratchet-wheel 37 secured to the shaft 19. Pivoted on the shaft 19 is a bell-crank lever 38, the short arm of which carries a spring-pressed pawl 39 which is set to engage a ratchet-wheel 40 secured on the shaft 19. The long arm of the bell-crank lever 38 is connected by a link 41 to a pivoted lever 42 which is set so as to be engaged by a pin 43 secured on a 110 disk 44 mounted on one of the power shafts 45 of the machine. In an ordinary operation, the shaft 19 is driven at a continuous speed through a gear wheel 18, gear wheel 35 and spring pawl 36 engaging the ratchet-wheel 37, but when the pin 43 engages the 115 end of the lever 42, the bell-crank lever 38 will be quickly oscillated in the direction indicated by the arrow which will cause the pawl 39 to engage and turn the ratchet-wheel 40 forward much faster than the ratchet-wheel 37 is being turned which will 120 impart a quick forward movement to the feeding rolls.

In the constant speed operation of the 1:

feeding rolls, the ratchet-wheel 40 turns forward under the pawl 39. As many pins 43 may be placed on the disk 44 as desired.

The improved form of gearing may be applied to a twisting machine in which no drawing is done, by simply using the gearing to drive rolls 10-10 which perform the function of feeding or forwarding the yarn or one strand of the yarn to the bobbin. In this case the quick forwarding action of the rolls 10-10 will give a different effect to that part of the yarn which is quickly advanced so as to give a novelty appearance.

Many other forms of gearing and arrangements may be devised for practising the improvement as previously described without departing from the scope of my invention as expressed in the claims.

Having thus fully described my invention, what I claim and desire to secure by Letters-Patent is:—

In a spinning or twisting machine, the combination of feeding rolls, intermediate rolls and drawing rolls, with a shaft connected with one of the drawing rolls, to rotate at

constant speed, an idle gear driven constantly from said shaft, a wheel loose on the shaft of one of the feed rolls meshing with said idle gear, driving connections between said shaft and wheel whereby said wheel will rotate said shaft at a constant speed but will permit the shaft to be intermittently rotated at a higher speed, means for intermittently rotating said shaft at said higher speed, means connected with said drawing roll shaft for rotating some of the intermediate rolls positively therefrom at constant speed, and means for driving the other intermediate rolls from the feed roll shaft and thereby varying their speed simultaneously with that of said feed roll.

In testimony whereof I have hereunto set my hand, in the presence of two subscribing witnesses.

SYLVANUS B. ROY.
